UNITED STATES PATENT OFFICE

EDGAR D. TILLYER, OF SOUTHBIDGE, MASSACHUSETTS, ASSIGNOR TO RADIO CORPORATION OF AMERICA, OF NEW YORK, N. Y., A CORPORATION OF DELAWARE

RADIO TELEPHONY RECEIVING APPARATUS

Application filed June 26, 1926, Serial No. 118,705. Renewed June 23, 1930.

The present invention relates to radio-telephony receiving sets and has particular reference to an improved receiving apparatus and methods of receiving the radio broadcast waves with the elimination or reduction of obnoxious noises in the reception of these waves.

The primary object of the invention is to filter the modulated carrier wave of a broadcasting station so that the general interferences accompanying the reception of the said wave may be greatly reduced or eliminated.

Another object of the invention is to provide means in a radio-telephony receiving apparatus whereby the modulated carrier wave of a broadcasting station may be filtered or tuned with such selectivity as to allow only a small portion of the said carrier wave to pass through the receiving apparatus, thereby greatly reducing or eliminating the general interferences usually accompanying the reception of the said modulated carrier waves.

Another object of the invention is to provide means in such a receiving apparatus that will filter the carrier wave along with means whereby the filtered carrier wave may be transformed to the equivalent of the original carrier wave of the broadcasting station so that it will be free from distortion and partially or absolutely free from the general static, ground and oscillating set interferences when heard by the listener.

Another object of the invention is to provide simple, efficient and inexpensive means for constructing an apparatus of the character stated.

Other objects and advantages of the invention should become apparent by reference to the following specification taken in connection with the accompanying drawings, and it will be understood that I may make any modifications in the specific arrangement of parts, details of construction and methods shown and described within the scope of the appended claims without departing from or exceeding the spirit of the invention. The preferred forms of the invention only have

been shown and described by way of illustration.

Present radio-telephony of the best receiving sets for broadcast reception have a certain limit to their selectivity in tuning, and this limit is due to the width of the audio frequency band it is desired to pass. For understandable speech it is necessary to pass all audio frequencies up to perhaps 2500 cycles per second and for music up to from 5000 to 6000 cycles, or perhaps more per second. It, therefore, has been necessary to allow a wide audio frequency band to pass through the receiving set so that music, speech, etc., will be free from distortion when heard by the listener.

As a means of illustration let us assume that (fr) is the radio frequency of the carrier wave of a broadcasting station; (fa) the audio frequency of any note or group of notes desired to be received; (fA) the maximum audio frequency or highest overtone it is desired to receive, and (FR) the radio frequency added by the first oscillator.

For example, a broadcasting station sends a carrier wave of a radio frequency (fr) modulated by music or speech at audio frequency (fa). There are many audio frequencies acting at the same time because speech and music are composed of many audio frequencies and any one of these many frequencies are representative of all, so we, therefore, need consider only one, as (fa). The previously unmodulated carrier wave of frequency (fr) is, when modulated by (fa), composed of three frequencies (fr plus fa , fr and fr minus fa), that is to say, one side band ($fr+fa$) carrier (fr) and the other side band ($fr-fa$) as well as harmonics of these frequencies, which are entirely outside of the tuning range when a receiving set is tuned to the fundamental frequency or which may not be transmitted at all, depending entirely on the transmitting circuit.

The present receiving sets, therefore, must tune broad enough to include all of these frequencies, fr plus fa , fr and fr minus fa , if no distortion is to be permitted, or with the least possible amount of distortion. This broadness of tuning is objectionable as it

introduces many undesired features, such as the general crashing static interferences, power ground interference, and interference of heterodyning stations, all of which tend to destroy the music or speech being received.

5 These interferences may be reduced or eliminated only by increasing the selectivity of tuning, and previous to the present invention this has not been accomplished except at the expense of eliminating the higher audio frequencies which give character to music, that is, the terms involving fa when this frequency is a high audio overtone.

10 It, therefore, becomes the most important object of this invention to provide a radio-telephony receiving set which shall be very selective in tuning and which shall filter the broadcasted radio wave so as to reduce or eliminate the interferences accompanying the 15 modulated carrier wave as heretofore stated, and which shall produce undistorted music or speech when heard by the listener.

20 Before the present invention if the tuning was increased in selectivity until only one band, that is, from $(fr \text{ to } fr \text{ plus } fa)$ or $(fr \text{ to } fr \text{ minus } fa)$ were passed, that is, just excluding or weakening fr , the result would be that a signal of double audio frequency or $2fa$ is detected, since when fr is weakened 25 the detected current has a frequency of $2fa$ and fa instead of fa alone.

30 This, of course, is no longer music or speech, so it is necessary to provide means whereby this distorted double frequency signal may be changed to the undistorted true representation of the original signal impressed on the original carrier wave.

35 This special receiver must be so selective in tuning that it will distinguish between $fr \text{ minus } fa$ and fr or $fr \text{ plus } fa$ and fr and then add the necessary fr or its equivalent from a local oscillator so that the audio component fa will be detected as fa and not $2fa$ or $2fa$ combined with fa .

40 By these transformations I produce a broadcast receiving set having probably more than twice the selectivity in tuning than that of previous sets of this character, reducing undesired disturbances and greatly increasing 45 selectivity. This increase in selectivity is so great that by proper adjustment of the circuits two heterodyning stations may be separated. This separation is accomplished by tuning on the two side bands which are 50 farthest away from each other. Likewise, the squeals and interferences from regenerating sets are reduced by at least one-half, as they will not be heard unless they are on the side of the station frequency the receiver is 55 tuned to pass. By a slight change in the tuning the other group of frequencies may be tuned in and the squeals thereby eliminated.

60 We can, as has been done in transatlantic 65 experiments, transmit only $fr \text{ minus } fa$ or fr

plus fa by introducing the proper power amplifier with a saving in power. The receiving system in this instance will detect the frequency as $2fa$ instead of fa unless a frequency of fr is added at the receiver which 70 then detects the frequency as fa . This requires a special transmitter which cannot be received on ordinary receiving sets. However, with the present broadcasting stations which do not eliminate the other two frequencies, fr and either $fr \text{ minus } fa$ or $fr \text{ plus } fa$, it becomes necessary in order to obtain the 75 advantage of the greatest possible selectivity in tuning to develop a special receiver for the reception of the present type of broadcasting, and it is with this in view and other objects 80 stated above that the present invention is designed so that the advantages which are obtained with special transmitters may be obtained with any standard transmitter and 85 any receiving set.

Referring more particularly to the drawings:

Figure 1 shows a diagram of one of the 90 methods in which a receiver of the character stated may be developed.

Figure 2 shows a diagram of another method in which a receiver may be developed.

In Figure 1 the circuit C1 is an ordinary circuit tuned to a band between say fr and $fr \text{ plus } fa$; the other band $fr \text{ to } fr \text{ minus } fa$ can be treated in the same way, so it will be only necessary to consider the $fr \text{ to } fr \text{ plus } fa$ band. This being an ordinary circuit, it will pass some $fr \text{ minus } fa$, these may be somewhat weaker but not greatly so. Circuit C5 is an oscillator giving a frequency of say FR which differs from fr by a low radio frequency. Then there will be an output as in the regular super-heterodyne of a frequency either first $fr \text{ minus } FA \text{ minus } FR$, $fr \text{ plus } fa \text{ minus } FR$ and $fr \text{ minus } FR$ or second $FR \text{ minus } fr \text{ minus } fa$ and $FR \text{ minus } fr$. The prior art circuit of the regular super-heterodyne corresponding to C2, C3 and C4 100 in Figure 1, must tune sufficiently broad to pass all of either the first group or the second group of frequencies previously stated if no distortion is to result. In order to obtain this 105 in the superheterodyne iron core transformers are often used.

In my combination, however, I make C2, C3 and C4 tune sufficiently selective to exclude completely either first $fr \text{ minus } fa \text{ minus } FR$ or, second, $FR \text{ minus } fr \text{ plus } fa$, no matter what values fa may have, always positive however, and also to exclude or greatly weaken either first $fr \text{ minus } FR$ and $fr \text{ plus } fa \text{ minus } FR$, or second, $FR \text{ minus } fr$ and $FR \text{ minus } FA \text{ minus } fr$ where FA is used to represent the limiting value of fa it is desired to receive. If this is then passed on to the detector in the circuit C4, a distorted audio frequency will be obtained, in general having a 110 115 120 125 130

frequency of twice the desired audio frequency.

The circuits C2, C3 and C4 are tuned to maximum response to a frequency midway between either first f_r minus FR and f_r plus f_A minus FR, or second, FR minus f_r and FR minus f_A minus f_r in order to obtain the foregoing result and can be permanently adjusted to one frequency as the difference between the frequency of the broadcasting station f_r to which C1 is tuned and the frequency of the oscillator FR is tuned so that their difference is constant, so C1 and C5 are variable while C2, C3 and C4 are fixed in tuning.

As previously stated, this gives a distorted double frequency response corresponding to a real sharply tuned superheterodyne and in order to eliminate or rectify this double frequency distortion C6 is added, permanently tuned to a frequency of either first f_r minus FR, or second, FR minus f_r , to add the transformed or the equivalent of the eliminated portions of the carrier wave frequency with a frequency that is clear and free from static and other interferences, thereby correcting the detected signal which is a distorted double frequency to an undistorted true representation of the original signal impressed on the original carrier wave. By these transformations we have produced a broadcast receiving set probably more than twice as selectively tuned as any previous set, thereby reducing extraneous undesired disturbances and greatly increasing selectivity.

Other circuits may be utilized to obtain the same filtering action or selectivity in tuning. As shown in Figure 2, a regular tuned radio frequency set may be so designed that only the band between f_r and f_r minus f_A or f_r and f_r plus f_A is passed, excluding both f_r and f_r minus f_A or f_r and f_r plus f_A , then adding f_r by a variable tuned circuit instead of the fixed one represented in C6, Figure 1.

This type of circuit is somewhat more difficult to construct because of the extremely low decrement required when the major frequencies are not separated to a greater interval before being tuned, as in Figure 1 circuit C5 and also require the copper or metallic casings A for each circuit, as illustrated in Figure 2 to form an extremely selective circuit.

The foregoing has been expressed in terms of mathematical frequencies, but the necessary data may be expressed in terms of the carrier wave f_r and the upper side band f_r minus f_A , and the lower side band f_r plus f_A . As has been previously stated, if only the waves between f_r minus f_A and f_r or f_r plus f_A and f_r are passed a double frequency distortion will be received, so to overcome this distortion the carrier frequency or its equivalent is added by a local oscillator.

Internal tube element capacities can be

balanced out by the usual methods as well as other circuit details not indicated. These are not illustrated for they are well known to those skilled in the art.

From the foregoing it will be seen that I have provided a new and novel radio telephony receiving apparatus with methods of making the same whereby the aforementioned carrier wave and side bands may be received on the antennae as they have been sent out by the regular broadcast station and then reduced or tuned with sufficiently selective circuits to pass only one side band, weakening the upper and lower edges of said band, then adding the carrier frequency or its equivalent so no double frequency distortion is produced.

Several methods may be used in carrying out the objects of the present invention, such as the super-heterodyne or shielded loose coupled circuits, etc., so I do not wish to limit myself to any one circuit. Those shown and described are used simply as a means of illustration.

From the foregoing description it will be seen that I have accomplished the objects of the invention by providing apparatus that will receive the transmitted modulated carrier wave which comprises the carrier wave itself and both side bands due to the audio frequency impressed on the carrier wave by its modulation at the transmitter and will filter out either before or after changing its frequencies the carrier wave itself and one of the side bands and then add a carrier wave equivalent to the eliminated carrier wave so that double frequency audio distortion will be eliminated and then providing means for detecting the added carrier wave combined with its single side band.

Having described my invention, I claim:

1. Receiving apparatus for a radio telephony set comprising means for receiving a modulated carrier wave, means for eliminating the carrier wave and one side band, means for generating a local carrier wave of the same frequency as the original unmodulated carrier wave, and means for combining the other side band with said locally generated carrier wave.

2. Receiving apparatus for a radio telephony set comprising a variable circuit to receive a modulated carrier wave, a series of low decrement tuned circuits to eliminate the carrier wave and one side band, an oscillator to generate a local carrier wave of a frequency equivalent to the original carrier wave, and means for combining the other side band with said local carrier wave.

3. The method of receiving a modulated radio telephony carrier wave comprising eliminating the carrier wave and one side band, and adding a carrier wave frequency equal to the eliminated carrier wave frequency and detecting the new modulated wave.

4. Receiving apparatus for a radio telephony set comprising means for receiving a modulated carrier wave comprising a carrier wave and its associated upper and lower side bands, means to filter out from said modulated carrier wave the carrier wave and one side band, means for adding a new carrier wave equivalent to the one filtered out, and means for detecting the new modulated wave.
- 10 5. Receiving apparatus for a radio telephony set comprising means for receiving a modulated carrier wave comprising a carrier wave and its associated upper and lower side bands, means for changing the frequency of the received carrier wave and its side bands, means for filtering out the changed frequency carrier wave and one side band, and means for adding a carrier wave equivalent to the changed frequency carrier wave, and means for detecting the new modulated wave.
- 15 6. A method of reception which consists in collecting a modulated carrier wave, suppressing the carrier and one side band, generating local oscillations having a frequency equal to the suppressed carrier frequency, combining the local oscillations with the remaining side band, and detecting the combined local oscillations and side band.
- 20 7. A method of reception which consists in collecting a modulated carrier wave, filtering the modulated wave to pass only one side band, generating a wave having a frequency equal to the original carrier wave frequency, combining the generated wave and the aforementioned side band, and detecting the combined band and wave.
- 25 8. A method which consists in collecting voice modulated carrier energy, suppressing the carrier and one side band, and combining the remaining side band with locally produced energy of a frequency equal to the suppressed carrier.
- 30 9. A method which includes collecting speech modulated carrier energy and suppressing the carrier and one side band, and combining the remaining side band with energy of a frequency equal to the aforementioned carrier frequency.
- 35 10. A method of receiving radio telephone waves without undesirable interference, which includes collecting such waves, attenuating the energy of the carrier and one of the side bands of the waves to the point of suppression, combining the remaining side band energy with energy of a frequency equal to the suppressed carrier frequency and free of interference frequencies, and detecting the combined energies.
